UNITED STATES PATENT OFFICE.

RALPH L. WINTERS AND JOHN H. WINTERS, OF CLARKSVILLE, TENNESSEE.

METHOD OF TREATING GARLICKY WHEAT.

Application filed June 20, 1923. Serial No. 646,630.

To all whom it may concern:

Be it known that we, RALPH L. WINTERS and JOHN H. WINTERS, citizens of the United States, residing at Clarksville, in the county of Montgomery and State of Tennessee, have invented certain new and useful Improvements in Methods of Treating Garlicky Wheat, of which the following is a specification, reference being had to the accompanying drawings.

This invention relates to a method of treating garlicky wheat to remove garlic and wild onions therefrom.

An important object of the invention is to provide a method of this character which may be carried out with the usual machinery employed in the mill with the exception of a small additional element for feeding a dehydrating compound to the wheat.

20 A further object of the invention is to provide a dehydrating compound for use in treating garlicky wheat which at the same time decomposes and dehydrates the garlic and onions.

25 A further object of the invention is to provide a method of treating wheat to eliminate garlic and onions therefrom in which heating of the wheat is eliminated, thereby eliminating the injurious effect to the wheat usually resulting from such treatment.

30 These and other objects we attain by the apparatus disclosed in the accompanying drawings in which the figure discloses a diagram showing the arrangement of the elements employed in carrying out the method.

35 In this diagram the numeral 10 designates a separator, such as commonly employed in mills, and the numeral 11 a scourer which is likewise of the usual construction. The 40 wheat leaving the separator is delivered to the scourer 11 by a conveyer 12 and from the scourer 11 passes through a worm conveyer 13 in which the wheat moves slowly and is thoroughly agitated, this conveyer leading to a storage bin 14. In accordance 45 with our invention we provide at the entrance end of the worm conveyer 13 a feeding device 15 of any suitable character by means of which a dehydrating element may be fed to the wheat as it passes through the conveyer and thoroughly mixed therewith, so that when the wheat and onions contained therein are discharged to the storage bin they are coated with this compound. As a 50 compound we preferably employ either hy-

drated lime or hydrated lime containing a small percentage of sodium bicarbonate.

As is well known to those familiar with the milling art, wheat in the process of preparation for milling is first passed through the ordinary cleaning machinery employed at the mill, consisting of the separator 10 and scourer 11, hereinbefore referred to. While the specific structure of these elements is not herein disclosed it is well known that a separator is effective to remove large grains or bulbs of garlic or onions and also those onion seedlets which are smaller than the mesh of the separating screens of the separator. These separators embody blowers for removing chaff and light onions and like substances from the wheat as they pass therethrough, accordingly, wheat which is passed through the separator will be free from all garlic except those portions approximately the same size and weight as the grains of wheat. This wheat is delivered to the scourer and during its passage through the scourer, due to the beating action to which it is subjected, the onion seedlets are bruised and the skins thereof broken, with the result that the juices from the seedlets escape and ordinarily attach themselves to the wheat with the result that the flour produced from the wheat has the odor of garlic and onion. In accordance with our invention, as the wheat leaves the scourer and is delivered to the conveyer 13, we intermingle therewith and with the onions contained therein, by means of the feeding device 15, hydrated lime which is thoroughly mixed with the wheat during its passage through the conveyer 13 so that it covers each and every part thereof. The lime covering the wheat absorbs not only the moisture freed by the crushed skins and bulbs of onions and garlic, but likewise completely eliminates the smell resulting from the crushing of these seeds. It has been found advisable to leave the wheat and onions intermingled with the dehydrating compound or lime in the storage bin 14 for at least five days, although better effects will be obtained by allowing the mixture of the composition and wheat to remain in the storage bin for fifteen to twenty-five days. No harm results to the wheat if the composition is allowed to remain in the storage bin for five or six months.

During the period of storage the composi-

tion absorbs the moisture of the onion and leaves the same in the form of a dried husk. When it is desired to use the wheat the wheat is again passed through the separator and 5 scourer with the result that the composition is separated from the wheat and at the same time the dried bulbs of the onions and garlic, being very light, will be removed by the air currents to which they are subjected in 10 the separator and scourer. Those bulbs which are shriveled and have considerable weight will be of such small size that they will pass through the screens of the separator in the process of separation and thus be 15 eliminated. In addition to the hydrated lime, above referred to, for use as a dehydrating compound, we have found it advisable to employ with the lime a small percentage of sodium bicarbonate, since it has been 20 found that this element has a tendency to speed up the decomposition of the onions and garlic and permitting the lime to act thereon much more rapidly. It has been found that 25 wheat treated in accordance with the foregoing is not only free from the odor of onion and garlic but that the loaf volume thereof is increased and the quality of the flour produced improved. It is found that wheat can be treated with this process at a cost not 30 exceeding three-quarters of a cent per bushel, except in excessive cases. It will, of course, be understood that in cases where an extreme 35 amount of garlic and onions are contained therein a greater amount of the dehydrating compound must be employed.

It will, of course, be obvious that the better the onions and garlic are torn up and bruised the more quickly the drying compound will act to completely dry them and 40 accordingly where an excessive amount of onions and garlic are contained in the wheat it is often advisable to pass the same through the separator and scourer several times before adding the drying compound thereto.

It will furthermore be obvious that other 45 dehydrating elements may be found suitable for this purpose and we accordingly do not limit ourselves specifically to the use of lime or a mixture of lime and sodium bicarbonate, except as hereinafter claimed. 50

We claim:—

1. The method of treating garlicky wheat, consisting in cleaning and scouring the wheat, adding to the wheat a dehydrating compound, storing the wheat for a prolonged 55 period to permit the dehydrating compound to act upon the onions and garlic contained therein and recleaning the wheat.

2. The method of treating garlicky wheat, consisting in cleaning and scouring the 60 wheat, adding to the wheat a comminuted dehydrating compound, thoroughly intermingling the compound and wheat, storing the wheat for a prolonged period to permit the dehydrating compound to act upon the 65 onions and garlic contained therein and recleaning the wheat.

3. The method of treating garlicky wheat, consisting in cleaning and scouring the wheat, adding to the wheat hydrated lime, 70 thoroughly mixing the lime and wheat, storing the wheat a sufficient length of time to permit the lime to act upon the onions and garlic contained therein and recleaning the wheat. 75

4. The method of treating garlicky wheat, consisting in treating the wheat to break the cells of the onions and garlic contained therein, thoroughly intermingling with the wheat a small percentage of lime, storing 80 the wheat a sufficient length of time to permit the lime to act upon and dehydrate the onions and garlic contained in the wheat.

In testimony whereof we hereunto affix our signatures.

RALPH L. WINTERS.
JOHN H. WINTERS.
